FIG. 2.

FIG. 3.

UNITED STATES PATENT OFFICE

2,008,593

JAR CLOSURE

Oscar F. Pedersen, Riverside, Ill., assignor to
 Phoenix Metal Cap Co., Inc., a corporation of
 New York

Application June 27, 1932, Serial No. 619,584

1 Claim. (Cl. 215—97)

The invention relates to new and useful improvements in jar closures, and more particularly jar closures of the type where a band presses the closure cap against the sealing gasket for sealing the jar.

An object of the invention is to provide a sealing band which is constructed so that the pressure against the closure cap is localized and centered over the ideal sealing point between the sealing band and the lip of the jar.

In the drawing:

Figure 1 is a view partly in section and partly in side elevation of a jar with the closure cap attached thereto and the jar sealed by the improved clamping band.

Figure 2 is an enlarged sectional view showing the closure cap and band assembled on the jar before the band is screwed down so as to clamp the closure to the jar.

Figure 3 is a similar view showing the band screwed down and the closure cap in tight sealed contact with the jar head.

The invention has to do with a jar closure which includes a jar closure cap provided with a channel in which is placed a sealing gasket. The jar closure with the sealing gasket is inverted and placed on the jar so that the sealing gasket contacts with the lip of the jar from the inside to the outside thereof, slightly overlying both the inside and outside edges of the jar lip. The jar closure is forced into sealing contact with the jar by a clamping band which may be secured to the jar in any suitable way but preferably by screw threads. The clamping band has an annular inwardly extending portion which overlies the jar closure and the inner edge of the annular portion is turned underneath and extends for a distance outwardly flat against the underface of the band. This undeturned portion provides a strengthening of the edge of the annular portion of the band and it also provides a contracting rib which engages the jar closure directly over the inside edge of the sealing lip of the jar which is the ideal sealing point. In this way the pressure on the closure is localized so as to bring about a very tight seal between the sealing gasket, the jar closure, and the lip of the jar.

Referring more in detail to the drawing, the jar is indicated at 1. The jar as shown is provided with a screw thread 2 which projects from the outer face of the neck of the jar. The jar neck terminates at its upper end in the usual form of rib 3. The jar is closed by a cap or jar closure 4 which is shaped so as to provide a channel 5 with a flange 6 at the outer edge thereof

which is adapted to extend down along the outer face of the jar. The jar closure has a depressed central portion providing the inner inclined wall 7, and this inner wall 7 together with the flange 6 forms a channel. Located in this channel is an elastic gasket 8. The gasket may be flowed into the channel when the closure is placed with the channel facing upward and the elastic sealing material allowed to dry or set so as to form on the closure an elastic closure gasket. This gasket may be otherwise formed and otherwise attached to the closure. The closure with the gasket applied thereto is inverted and placed on the jar. The gasket extends all the way across the lip of the jar and overhangs the inside edge 15 of the lip and also the outside edge of the lip.

The closure is forced into sealing contact with the jar by a clamping band 9. This clamping band extends down alongside of the neck of the jar and is provided with a thread which cooperates with the threads 2 on the jar neck. Said band has an inwardly projecting annular portion 10 which is provided with an annular bead 11 for strengthening the same. The inner edge of the portion 10 is folded back underneath as indicated at 12. This undeturned portion is placed flat against the underface of the annular inwardly projecting portion of the band. The undeturned portion 12 thus provides a relatively narrow rib or band which contacts with the outer face of 30 the jar closure 4. This initially is the sole contact between the screw band and the jar closure. The contacting surface of the screw band is therefore localized and centered directly over the inside of the lip on the jar. This is the ideal sealing point. The pressure of the rib against the jar closure will force the sealing material downwardly and inwardly along the inside lip of the jar 6 making a very tight sealing line. This sealing line is indicated at a in Figure 3 of the 40 drawing.

From the above it will be apparent that a closure has been provided for a jar wherein a sealing band through the localized pressure at the ideal sealing point brings about a very tight seal between the closure cap, sealing gasket and the lip of the jar. It is obvious that the clamping band may be otherwise connected to the jar so that it will be drawn into tight clamping contact with the jar closure. The essential feature of applicant's invention is not in the screw connection between the band and the jar, but in the formed rib on the underface of the inwardly projecting portion of the band which localizes the gripping pressure on the jar closure. It will 55

be obvious that this localized pressure at the inner edge of the clamping band may be otherwise obtained without departing from the spirit of the invention as set forth in the appended claim.

5 Having thus described the invention, what I claim as new and desire to secure by Letters Patent, is:

The combination of a jar having a sealing lip at its open upper end and a screw thread adjacent said lip, a closure cap having a channel in the under face thereof adapted to receive the sealing lip of the jar, a sealing gasket in said channel between said lip and the closure cap and overlying said lip at the inner and outer edges 10 thereof, a clamping band having a skirt provided with a screw thread adapted to engage the

screw thread on the jar, and an overlying portion adapted to contact with the closure cap, said overlying portion having a strengthening bead formed therein, the inner edge of said overlying portion being folded underneath and upon itself and disposed so as to lie wholly in the region directly above the inside edge of the lip of the jar, said underneath folded portion extending all the way around said closure cap and disposed in a plane beneath the outer edge of the overlying portion and serving as the sole means of contact between the clamping band and the closure cap whereby the pressure of the band is localized on the cap directly over the inside edge of the lip of the jar. 10 15
